WELT INDENTING MACHINE

Corwin W. Baker, Hamilton, Mass., assignor to
 United Shoe Machinery Corporation, Flemington, N. J., a corporation of New Jersey

Application July 27, 1949, Serial No. 107,033

6 Claims. (Cl. 12—32)

1

This invention relates to welt-indenting machines and is herein disclosed as embodied in a machine of the type illustrated and described in United States Letters Patent No. 2,358,787, granted September 26, 1944 upon the application of Irving E. Booth. Such machines are in common use for making indentations to form a uniform decorative design upon the welts of shoes or upon the upper surfaces of the projecting margins of the soles of shoes which are not provided with welts. In a machine of this type the operating instrumentality consists of a frusto-conical toothed wheel which is freely and idly rotatable and which is urged periodically against the work piece by a crank and linkage mechanism; and the work support consists of a driven turntable which may be adjusted to any desired position in the direction of feed and to any desired angle of inclination, the work support being yieldingly held against the pressure of the indenting wheel by a spring and being also momentarily supported against the rapid impulses of the indenting wheel by an inertia block.

It is an object of the present invention to provide a welt indenting machine of the type under consideration having a simplified operating mechanism. In accordance with this object, the mechanism for operating the indenting wheel of the illustrated machine consists of a connecting rod which carries the indenting tool and which is driven by a crank, the connecting rod being fulcrumed upon a pivotal support carried by a free end of a guide link the opposite end of which is pivotally mounted for swinging movement about a stationary pivot. The indenting wheel, by reason of this construction, is free from the rotational frictional drag to which it would be subject if mounted directly upon the crank. In accordance with another feature, the crank which drives the connecting rod comprises a crank pin carried by an eccentric which may be rotated for purpose of adjustment with respect to a shaft which carries the eccentric, such adjustment serving to vary the throw of the crank pin about the axis of the shaft. The amplitude of the impulses imparted to the indenting wheel by the crank pin can be varied by this adjustment.

These and other features of the invention will appear more fully from the following detailed description when read in connection with the drawings and will be pointed out in the appended claims.

Referring now to the accompanying drawings,

2

Fig. 1 is a side elevation of an illustrative machine embodying the invention;

Fig. 2 is a side elevation, on a larger scale, of the upper portion of the machine shown in Fig. 1;

Fig. 3 is a sectional side elevation drawn on a still larger scale showing the operating and work supporting instrumentalities in engagement with a shoe;

10 Fig. 4 is a view in perspective of the forepart of a shoe showing the indentations formed in the welt by the illustrated machine;

Fig. 5 is a front elevation of the upper portion of the machine;

15 Fig. 6 is a front elevation of the mechanism for driving the indenting wheel adjusted for zero throw of the crank pin;

Fig. 7 is a view similar to Fig. 6 adjusted for maximum throw of the crank pin;

20 Fig. 8 is a detail sectional view of the indenting wheel and its mounting;

Fig. 9 is a front elevation of the treadle mechanism;

Fig. 10 is a sectional view taken on the line

25 X—X of Fig. 2;

Fig. 11 is an exploded view of the worktable and its supporting mechanism; and

Fig. 12 is a detail in front elevation, partly in section, of some of the parts shown in Fig. 11.

30 The work-engaging members of the illustrated machine consist of a frusto-conical toothed indenting wheel 10, a guard 12 for protecting the upper of a shoe S (Fig. 3) from the wheel 10 and serving also as a gauge against which the upper of the shoe is held, and a rotary driven worktable 14 for supporting the shoe. The indentations formed by the indenting wheel 10 upon the welt of the shoe S are shown in Fig. 4.

35 The supporting structure of the machine consists of a column 16 which carries a head or frame having a base 18, a front wall 20, a rear wall 22, and a cover 24.

The indenting wheel 10 is mounted for free rotation upon a pin 26 (Figs. 3, 6, 7 and 8) to the

40 forward end of which may be welded the guard 12. The pin 26 is clamped by a set screw 28 in the lower end of a connecting rod 32. The indenting wheel is spaced from the front face of the connecting rod 32 by a washer 30 on the pin 26. The upper

45 end portion of the connecting rod 32 is in the form of an eccentric strap 33 and it carries the outer raceway of a ball bearing 34 (Fig. 3), the inner raceway of which is mounted upon the forward end portion of a crank pin 36. The

50 crank pin 36, upon which the connecting rod 32

is thus journaled, is secured in an eccentric bore formed in a sleeve 38 which is secured in an eccentric bore formed in the forward end of a shaft 40. A set screw 42 holds the eccentric sleeve 38 in any desired position of rotary adjustment with respect to the shaft 40 and a set screw 44 holds the crank pin 36 securely in the bore of the eccentric sleeve 38. The inner race-way of the ball bearing 34 is retained against axial movement on the crank pin 36 by the forward face of a flange on the eccentric sleeve 38 and also by a washer 46 which is clamped by a nut 48 against a shoulder on the crank pin.

The shaft 40 is journaled at its forward end portion in a bearing 50 carried by the front wall 20 and its rear end portion in a bearing 52 carried by the rear wall 22. Upon a rearward extension of the shaft 40 is a pulley 54 which is driven by a belt 56 from a pulley 58 (Fig. 1) on the shaft of a motor 60. The shaft 40 is thus driven in a counterclockwise direction, as seen from the front of the machine.

For controlling the motion of the connecting rod 32, there is provided a fulcrum in the form of a pivot pin 62 (Figs. 6 and 7) located at an intermediate portion of the connecting rod between the indenting wheel 10 and the crank pin 36. The pivot pin 62 constitutes a pivotal connection between the connecting rod and the left-hand end of a guide link 64, the right-hand end of this link being pivotally mounted upon a stationary pin 66 secured in the front wall 20. It is evident that rotation of the shaft 40 will rock the connecting rod 32 about the fulcrum 62 and that the link 64 will swing up and down to permit the connecting rod to move heightwise, the lateral displacement of the fulcrum 62 being negligible. An arcuate slot 67 formed in the connecting rod 32 and centered about the pin 66 (when the connecting rod is at the mid-point of its stroke) enables the pivot pin 62 to be adjusted up or down to vary the length of stroke in the direction of feed. The effect of rotary adjustment of the eccentric sleeve 38 is shown in Figs. 6 and 7. Fig. 6 shows the sleeve 38 as having been turned into a position wherein the axis of the crank pin 36 coincides with the axis of the shaft 40 and with this adjustment the connecting rod 32 will be motionless. Fig. 7 shows the eccentric sleeve 38 adjusted for a maximum stroke of the crank pin 36 in which adjustment the indenting wheel 10 will be driven in an orbital path and will thus be urged periodically toward and from the work and also rolled along the surface of the work back and forth along the path of feed. The maximum eccentricity provided by adjustment of the eccentric 38 is $\frac{1}{2}$ ". and the maximum diameter of the path of movement of the indenting tool 10 is about $\frac{1}{8}$ " when the pin 62 is adjusted in the slot 67 to a point midway between the crank pin 36 and the indenting tool 10. The indenting tool is heated by a stationary gas jet 68 which directs a flame against a rearwardly extending end portion of the pin 26.

The worktable 14 is carried upon the forward end of a yoke-shaped bracket comprising a pair of parallel arms 70 which incline upwardly and rearwardly from an integral cross bar 72. The arms 70 embrace the column 16 and also the base plate 18 and their rear ends are pivotally mounted upon a pair of coaxial pins 74 secured in ears 76 on the ends of a cross bar 75 clamped by screws 77 to the base plate 18. Extending upwardly from each of the arms 70 is a lug 78. 75

These lugs 78 slidably engage the lateral edges of the base plate 18 to guide and steady the arms 70 in their rising and falling movements. Extending between the lugs 78 is an integral cross piece 80 through which is upwardly threaded a stop screw 82. A lock nut 84 holds the stop screw 82 in adjusted position. The upper end of the screw 82 engages the under surface of the base plate 18 to limit the upward movement of the arms 70 and, therefore, of the worktable 14.

The worktable 14 is supported by a treadle mechanism which is connected to the cross bar 72 by a fitting having a downwardly extending ear 86 (Figs. 2 and 3) and a horizontal flange 88. A pair of clamping screws 90 secure the flange 88 to an offset central portion 91 (Fig. 11) of the cross bar 72. A pin 92 pivotally connects the ear 86 to a downwardly extending rod 94 having a threaded lower portion 96 upon which is threaded a sleeve 98 having at its upper end an integral knurled disk 100 to facilitate upward and downward adjustment of the sleeve 98 upon the rod 94. A lock nut 102 holds the sleeve 98 in adjusted position. Slidably engaging the outer surface of the sleeve 98 is a heavy inertia block 104 which extends down below the sleeve 98 and which has a downwardly extending bore coaxial with the sleeve 98. The upper end portion of a rod 106 slidably engages this bore. Secured upon the rod 106 by a set screw 108 below the inertia block 104 is a collar 110. A coil compression spring 112 surrounding the rod 106 has its lower end resting upon the collar 110 and its upper end in engagement with the under surface of the block 104 to support the block yieldingly. The lower end of the rod 106 (Fig. 1) is pivotally connected by a pin 114 to an arm 116 which extends up from a fulcrum pin 118 upon which it is pivotally mounted. Integral with the arm 116 and extending forward therefrom is a treadle 120. A tension spring 122 having one end anchored upon a stationary post 124 and its other end secured to the arm 116 normally holds the arm 116 upright against stop screw 126 threaded through a stationary portion of the machine frame. It is evident from the foregoing description that the arm 116 and the rod 106 together constitute a toggle which is normally held in straight position by the spring 122 to support the inertia block 104 and the worktable 14 in working position. This toggle can be broken by depressing the treadle 120, thereby permitting the inertia block and with it the worktable 14 to descend under the influence of their own weight. 55 The purpose of lowering the worktable 14 is to facilitate the introduction of a work piece.

The worktable 14 consists of a rotary disk having a stem 128 (Figs. 3 and 11) extending down through a bearing block 130. The lower portion of this bearing block 130 is in the form of a dovetail arcuate slide 132 having for its axis of curvature a line tangent to the periphery of the upper surface of the worktable 14 and perpendicular to the axis of the indenting wheel 10. Formed upon the slide 132 are rack teeth 134. A pinion 136, which is integral with a shaft 138, engages the rack 134 to vary the angular adjustment of the worktable 14. The shaft 138 is journaled for rotation in a block 140 and has at one end a knurled head 142 to facilitate turning. The block 140 has an arcuate dovetail guideway in which the slide 132 is slidable. A similar arrangement for adjusting the angular position of the worktable is disclosed in United States Letters Patent No. 1,357,511, granted No-

vember 2, 1920, upon the application of Frederick H. Perry. The block 140 has also a depending dovetail 144 which is slidably mounted for purposes of transverse (i. e., in the direction of feed of the work) adjustment in a complementary groove formed in a pair of parallel walls 146 which connect the offset 91 to the main portion of the cross bar 72. Adjustment of the dovetail 144 to bring the axis of the worktable 14 to the left of the center of the guard 12 will cause the rotating worktable to exert a component of cross feed which holds the upper of the shoe against the guard, the magnitude of this component depending upon the extent of the adjustment. A kerf 148 is cut into the walls 146 to provide for clamping and unclamping of the dovetail 144. A pair of screws 150 serve to clamp the dovetail 144 in its adjusted position.

The stem 128 has a downward extension 152 of reduced diameter which passes down through a slot 154 formed in the block 140. The lower end of the extension 152 is connected by a universal joint 156 to the upper end of a drive shaft 158 (Fig. 2). The lower portion of the drive shaft 158 is slidably keyed to a telescopic sleeve 160 which itself is keyed to a drive shaft 162 (Fig. 1). The lower end of the drive shaft 162 is connected by a universal joint 164 to the upper end of a shaft 166 which is driven through reduction gearing 168 by a pulley 170 and belt 172 from a pulley 174 driven by the motor 60.

In operating the machine, the operator lowers the worktable 14 by depressing the treadle 120 and he then inserts the projecting margin of the sole of the shoe S between the indenting tool 10 and the worktable 14. Upon his release of the treadle 120, the spring 122 draws the arm 116 inwardly and straightens the toggle formed by the arm 116 and the rod 106. The worktable 14 is thus, except for the spring 112, supported rigidly. The spring 112 yields to accommodate soles of different thicknesses and also local variations of thickness in the same sole; the inertia block 104 however does not yield quickly enough to respond to the rapid individual movements of the indenting tool 10 and so far as these movements are concerned it may be considered as affording a stationary support to the work piece. The crank pin 36 causes the upper end of the connecting rod 32 to move in a circular path and the pivotally mounted link 64 constrains the movement of the fulcrum pin 62 to a linear path which, because of its small amplitude, may be considered as substantially straight. The linear movement of the fulcrum and the oscillatory movement of the connecting rod about the fulcrum provide two components of motion for the indenting tool, the resultant of which components is an orbital movement in a clockwise direction as seen in Figs. 5, 6 and 7. The amplitude of this movement is never great enough to raise the teeth of the indenting wheel 10 out of contact with the work and it is too rapid to permit the spring 112 to force the inertia block 104 up each time the indenting tool 10 is raised. The teeth of the indenting tool 10, as the indenting tool is retracted, are in non-slipping engagement with the work and the new indentations formed by the advance stroke of the indenting tool will therefore be in register with the indentations already formed. The movement of the indenting tool back and forth along the line of feed is so rapid as to insure the teeth re-entering several times the already formed indentations and deepening them. An advantage in mounting the indenting tool upon the connecting rod 32 rather

than directly upon the crank pin 36 is that the frictional effect of the rapidly rotating crank pin is not transmitted to cause undesired rotation of the indenting tool.

Having described my invention, what I claim is new and desire to secure by Letters Patent of the United States is:

1. In a welt indenting machine, an indenting tool and mechanism for imparting to said indenting tool an orbital motion, said mechanism comprising a driven shaft, fixed bearings in which said shaft is journaled, an eccentric driving member on the shaft, a connecting rod journaled upon and driven by the driving member and carrying the indenting tool, a fulcrum about which the driving member rocks the connecting rod to impart to the indenting tool an oscillatory component of motion along the surface of a work piece, and means associated with the fulcrum for enabling the driving member to move the connecting rod toward and from the work piece and thereby impart to the indenting tool a periodically reversing component normal to the surface of the work piece.

2. In a welt indenting machine, an indenting tool and mechanism for imparting to said indenting tool an orbital motion, said mechanism comprising a driven shaft, an eccentric driving member on the shaft, a connecting rod carrying the indenting tool and having a bearing on the eccentric driving member whereby the connecting rod is driven, a movable fulcrum upon which the connecting rod is pivotally mounted, and means for constraining the movement of said fulcrum to a linear path, the linear movement of the fulcrum and the oscillatory movement of the connecting rod about the fulcrum thus providing two components of motion for the indenting tool, which components are compounded into an orbital motion.

3. In a welt indenting machine, an indenting tool and mechanism for imparting to said indenting tool an orbital motion, said mechanism comprising a driven shaft, an eccentric driving member on the shaft, a connecting rod carrying the indenting tool and having a bearing on the eccentric driving member whereby the connecting rod is driven, a guide link, a pivotal support for one end of the guide link, and a pivotal connection between the other end of the guide link and the connecting rod to serve as a fulcrum about which the connecting rod can swing as it is driven by the eccentric driving member.

4. In a welt indenting machine, an indenting tool and mechanism for imparting to said indenting tool an orbital motion, said mechanism comprising a driven shaft, an eccentric driving member on the shaft, a connecting rod carrying the indenting tool and having a bearing on the eccentric driving member whereby the connecting rod is driven, a guide link, a pivotal support for one end of the guide link, and a pivot pin at the other end of the guide link for pivotally connecting the guide link and the connecting rod, said connecting rod having a slot in which said pivot pin can be secured in various positions of adjustment to vary the radial distance of the pivot pin from the axis of the driven shaft and thereby to vary the orbital path of the indenting tool.

5. In a welt indenting machine, an indenting tool and mechanism for imparting to said indenting tool a periodic motion, said mechanism comprising a driven shaft, an eccentric carried by said shaft and rotatable with respect thereto for the purpose of adjustment, means for holding the

eccentric in adjusted position, a crank pin carried by the eccentric and having its axis offset from the axis of the eccentric whereby rotary adjustment of the eccentric will vary the throw of the crank pin about the axis of the shaft, and means for transmitting movement from the crank pin to the indenting tool.

6. In a welt indenting machine, an indenting tool and mechanism for imparting to said tool a periodic motion, said mechanism comprising a 10 driven shaft having an eccentric bore in one of its ends, an eccentric mounted in said bore and rotatable therein for the purpose of adjustment, means for holding said eccentric in adjusted position, a crank pin carried by the eccentric and extending beyond the end of the shaft, said crank pin having its axis parallel to and offset from the axis of the eccentric whereby rotary adjustment of the eccentric will vary the throw of the 15

crank pin about the axis of the shaft, and a connecting rod for transmitting movement from the crank pin to the indenting tool.
